United States Patent Office

Des. 195,280
Patented May 21, 1963

195,280

JUG

Ted F. Bodenheimer, Kansas City, Mo., assignor to Owens
Plastics Company, Kansas City, Mo., a corporation of
Missouri

Filed Dec. 4, 1962, Ser. No. 72,717

Term of patent 14 years

(Cl. D58—5)

Fig. 1.

Fig. 2.

Fig. 3.

Fig. 4.

FIG. 1 is a top plan view of a jug embodying my new design;

FIG. 2 is a bottom plan view thereof;

FIG. 3 is a front elevational view thereof; and

FIG. 4 is a side elevational view thereof.

The rear and side not shown are, respectively, substantially like the front and side shown in FIGS. 3 and 4.

I claim:

The ornamental design for a jug, substantially as shown and described.
